Examiner
Sodium phosphate
Sodium hypochlorite

Patented Dec. 4, 1923.

1,475,932

UNITED STATES PATENT OFFICE.

THOMAS W. CAPPON, OF NEWARK, NEW JERSEY.

INK ERADICATOR.

No Drawing.

Application filed December 15, 1921. Serial No. 522,692.

To all whom it may concern:

Be it known that I, THOMAS W. CAPPON, a citizen of the United States, residing at Newark, State of New Jersey, have invented a certain Improvement in Ink Eradicators, of which the following is a specification.

The present invention relates to an improved method for removing from paper and fabric lines and spots of ink or other substances as well as to a stable and relatively inexpensive composition which can be used for this purpose leaving the ink bearing surface uninjured.

15 It is a prominent advantage of this composition that it supplies the long felt want for a commercial one-fluid eradicator. The rapid and complete action achieved by this composition is another feature of advantage.

20 The present compound is a mixture of two solutions, one of which acts as an oxidizer while the other solution which is of a nature not to be oxidized by the first 25 named, acts as a decolorizer for the material resulting from the action of the oxidizer. For this purpose I have found that the reagents named below have the qualities named, and operate, each in its 30 own way, to accomplish the desired results.

25 My preferred oxidizer is a solution of a hypochlorite of an alkali metal, preferably sodium. This solution should be fairly strong and I have found a ten percent solution quite practicable.

30 Ordinary hypochlorite is generally too alkaline in its reaction, and enough dilute hydrochloric acid should be added to make the solution faintly alkaline as tested with 35 litmus paper.

40 The other fluid is a solution of any reagent which will not be oxidized by the hypochlorite and which has the property of forming a white or very light colored 45 precipitate in its reaction upon the salts produced by the hypochlorite.

45 For this latter purpose three salts have been found useful in solution, namely, the ortho-phosphate, the pyrophosphate and 50 the metaphosphate of an alkali metal. These are named in the ascending order of usefulness.

55 The orthophosphate of sodium (for instance) reacts upon the iron salts resulting from the hypochlorite to form a very light

yellow substance; so that, while this salt may be used for some purposes, it cannot be said to give the best results.

The pyrophosphate gives a better result, although especially after a lapse of some 60 time, a very faint greyish line can be detected where the eradication has taken place. This salt has in its favor, however, the fact that it is perfectly stable. Even prolonged boiling causes no decomposition. 65

The best results are produced by the metaphosphate. Where this salt is used, the resultant reaction leaves a substance as 70 white as the paper itself, and therefore practically invisible.

75 The orthophosphate is, of course, the salt corresponding to orthophosphoric acid. The other two salts named are made from more or less dehydrated orthophosphoric acid, since pyrophosphoric acid results from removing one molecule of water from two molecules of orthophosphoric acid, and metaphosphoric acid results from removing two molecules of water from two molecules of orthophosphoric acid. As above pointed out, the salts made from more or less dehydrated acid are distinctly superior to the orthophosphates in this connection. 80

85 As an example of proportions that have been found satisfactory in practice, the following may be mentioned.

With the hypochlorite solution of the strength above stated, the orthophosphate of sodium (for instance) may be used in a saturated solution in the proportion of one 90 part of orthophosphate to three parts of hypochlorite. The pyrophosphate in saturated solution may be used in the proportion of one part of the pyrophosphate to three of hypochlorite. The metaphosphate 95 in four or five percent solution may be used in the proportion of one of the metaphosphate to four of the hypochlorite. These proportions are by volume, and they may be greatly varied without departing 100 from the invention, which is not limited to the proportions stated.

105 By using an excess of the above described mixture and leaving it for a while upon the spot or line to be eradicated, the precipitate formed may be entirely dissolved and removed as well as being decolorized, especially where the ink contains organic matter.

110 This compound is not alone useful for

inks, but is highly effective in removing fruit stains, blood-stains, etc.

While the ingredients above set forth have been herein described as being mixed to form a one-fluid eradicator, it is evident that the improved process forming the basis of this invention may be carried out in practice by supplying the hypochlorite in one solution and the other ingredient in a separate solution, permitting the user to form the mixture directly on the ink mark to be treated.

What is claimed is—

1. The process of eradicating ordinary inks from paper and other materials of the character described which consists in subjecting the ink line or spot to the action of an alkali hypochlorite and immediately decolorizing the resulting product by treating the same with an alkali phosphate.

2. The process of eradicating ordinary inks from paper and other materials of the character described which consists in subjecting the ink line or spot to the action of an alkali hypochlorite and immediately decolorizing the resulting product by treating the same with an alkali phosphate made from more or less dehydrated orthophosphoric acid.

3. The process of eradicating ordinary inks from paper and other materials of the character described which consists in subjecting the ink line or spot to the action of an alkali hypochlorite and immediately de-

colorizing the resulting product by treating the same with an alkali metaphosphate.

4. A single fluid eradicator comprising a mixture of an alkali hypochlorite with an alkali phosphate.

5. A single fluid eradicator comprising a mixture of an alkali hypochlorite with an alkali phosphate made from more or less dehydrated orthophosphoric acid.

6. A single fluid ink eradicator comprising a mixture of an alkali hypochlorite with an alkali metaphosphate.

7. A single fluid ink eradicator comprising a mixture of sodium hypochlorite and sodium metaphosphate.

8. A single fluid eradicator comprising a mixture of two solutions one of which is an alkali hypochlorite and the other of which is incapable of material oxidation by the first named solution and acts as a decolorizer.

9. The process of eradicating inks from paper and other materials which consists in applying to the ink line or spot an alkali hypochlorite and an alkali phosphate more or less dehydrated in such a manner that both of said reagents are present upon the line or spot at once, substantially as described.

In testimony whereof I have hereto set my hand on this 13th day of December, 1921.

THOMAS W. CAPPON.

DISCLAIMER

1,475,932.—*Thomas W. Cappon*, Newark, N. J. INK ERADICATOR. Patent dated December 4, 1923. Disclaimer filed January 16, 1937, by the patentee and the assignee of one-half interest, *Cardinell Corporation*.

Hereby enter the following disclaimer to claim 8:
Petitioners disclaim from the scope of claim 8 any single fluid eradicator in which the solution acting as a decolorizer is not an alkali phosphate.
